UNITED STATES PATENT OFFICE.

THOMAS B. PEACOCK, OF TOPEKA, KANSAS.

ADVERTISING-WINDMILL.

SPECIFICATION forming part of Letters Patent No. 274,651, dated March 27, 1883.

Application filed October 17, 1882. (No model.)

To all whom it may concern:

Be it known that I, THOMAS BROWER PEACOCK, of Topeka, in the county of Shawnee and State of Kansas, have invented a new and Improved Advertising-Windmill, of which the following is a full, clear, and exact description.

The object of my invention is to provide a new and improved windmill which is to be provided with advertisements, and which is to operate musical instruments to attract the attention.

The invention consists in the combination, with a windmill, of revolving disks and drums carrying advertisements, and of bells, a triangle, and musical instruments, all of which are operated by the windmill, so as to call the attention of passers-by to the advertisements on the mill and on the wheels and drums on the same.

20 The invention further consists in the combination, with the mill, of a figure with movable limbs, which figure is operated and moved by the wind-wheel.

The invention also consists in details and 25 parts of construction and combinations of the same, as will be fully set forth and described hereinafter.

Reference is to be had to the accompanying drawings, forming part of this specification, in 30 which similar letters of reference indicate corresponding parts in all the figures.

Figure 1 is a longitudinal elevation of my improved windmill, parts being shown in section. Fig. 2 is a front elevation of the same. 35 Fig. 3 is a detail elevation of part of the mechanism for transmitting motion.

The crank-shaft A of a wind-wheel, A², of any suitable construction, is journaled in standards A', projecting from the upper end of a 40 vertical tube, B, which is suitably journaled in the frame C. The hinged vane B' is attached to one of the standards A'. A rod, D, passes through the tube B, and is connected, by means of a connecting-rod, D', with the crank a of the shaft A. A rope, E', fastened to the vane B', passes through eyes and loops on the tube B, down through the said tube, and is secured on a cross-piece, b, of the rod D. By means of the said rope the vane can be adjusted and 45 held in the desired position. The rod D passes

through and is connected with a bar, E, pivoted to, and passing transversely across the frame C, which bar E has a rod, E'', attached to its free end, the said rod passing into a triangle, F, or striking a gong which is suspended from a cord attached to the frame C, causing the triangle or gong to be sounded. A disk or wheel, G, is mounted on the outer end of a horizontal shaft, H, journaled in the upper part of the frame C, on which shaft are mounted a pulley, J, and a ratchet-wheel, K. A rod, L, is pivoted to the bar E, and to an arm, M, which is hooked on or pivoted to the shaft H. A pawl-lever, N, has one end resting against the teeth of the ratchet-wheel K, and the other end is drawn downward by an elastic cord or spring, O, which is fastened to the end of the pawl-lever and to the rod L, whereby the end of the pawl-lever will be pressed against the teeth of the ratchet-wheel. A cord or belt, P, passes over or through an annular groove in the pulley J, and over a pulley, Q, which is mounted on the shaft of a barrel-organ, R, or some other suitable similar musical-instrument. A cord or belt, S, passes over the pulley J, in an annular groove in the same, passes over a pulley, S', and a pulley, T', mounted on the upper-end of a drum, T, journaled in the frame C in such a manner that its longitudinal axis is vertical. A series of gongs or bells, V, forming a chime, 75 are suspended from a cord or wire, d, fastened to the frame C, and a cord or wire, f, connects the wire d with the bar E. The front of the frame C is covered with boards, and on the same the figure of a man, U, provided with 80 movable ears, arms, and legs, is secured, and the said ears, arms, legs, &c., are connected by cords or wires U' v with the bar E. Signs are painted on the wheel A² and the vane B', and the board cover of the frame C, the disk G, the 85 figure U, and the drum T are all covered with advertisements, pictures, show-cards, &c. When the wind turns the wheel A² it works the rod D up and down, and the same in turn works the bar E up and down, thereby causing 90 the rod E'' to strike the triangle F or gong. At the same time the cords or wires f and v are drawn taut by the bar E, and thereby the gongs or bells V will be vibrated or shaken and 95 sounded, and the ears, arms, and legs of the 100

figure U will be moved. By the movements of the bar E the rod L will be reciprocated vertically, whereby the pawl-lever N, which catches on the teeth of the ratchet-wheel K, rotates the said wheel when the rod L moves upward, but not when the same moves downward. The pulley J and the disk or wheel G will also be rotated, and the belts or cords P S, passing over the pulley J, rotate the drum T and work the barrel-organ R. As the ratchet-wheel K is only rotated when the bar L moves upward, the disk G and the drum T will not be rotated continually, but will stop at certain regular intervals, so that the signs can be seen and read conveniently.

Having thus described my invention, what I claim as new, and desire to secure by Letters Patent, is—

1. The combination, with an advertising-windmill, of a chime or gongs, a triangle, and an organ operated by the wind-wheel, substantially as herein shown and described, and for the purpose set forth.

2. The combination, with an advertising-windmill, of a chime and a triangle operated by the wind-wheel, substantially as herein shown and described, and for the purpose set forth.

3. The combination, with an advertising-windmill, of the disk G, the drum T, the bells V, the triangle F, the organ R, and the figure U, having movable limbs, substantially as herein shown and described, and for the purpose set forth.

4. In an advertising-windmill, the combination, with the wind-wheel A², of the rod D, the bar E, the rod L, the pawl-lever N, the ratchet-wheel K, the shaft H, the pulley J, and devices operated from the said pulley by means of ropes or belts, substantially as herein shown and described, and for the purpose set forth.

5. In an advertising-windmill, the combination, with the wind-wheel A², of the rod D, the bar E, the rod L, the pawl-lever N, the ratchet-wheel K, the shaft H, the disk G, the pulley J, the belts or ropes P and S, the drum T, and the organ R, substantially as herein shown and described, and for the purpose set forth.

6. In an advertising-windmill, the combination, with the wheel A² and rod D, of the pivoted bar E, connected to the said rod, and intermediate mechanism for operating the gongs, triangle, organ, and figure from the said pivoted bar, substantially as and for the purpose set forth.

7. In an advertising-windmill, the combination, with the wind-wheel A², of the rod D, the bar E, the figure U, having movable limbs, and the wires or cords U' v, substantially as herein shown and described, and for the purpose set forth.
